Assistant Examiner — Eidiol Ghigliotti Torres

(57) **CLAIM**

The ornamental design for an air pump, as shown and described.

DESCRIPTION

1. Air pump

1.1 : Perspective

1.2 : Perspective

1.3 : Front

1.4 : Back

1.5 : Left

1.6 : Right

1.7 : Top

1.8 : Bottom

The parts shown by means of broken lines in the reproductions are not part of the claimed design.

1 Claim, 8 Drawing Sheets(56)
